GOVERNOR FOR INTERNAL COMBUSTION ENGINES

Johannes Weber, Stuttgart-Feuerbach, and Hans Heinrich, Stuttgart, Germany, assignors to Robert Bosch Gesellschaft mit beschränkter Haftung, Stuttgart, Germany

Application July 14, 1936, Serial No. 90,588
In Germany July 29, 1935

12 Claims. (Cl. 123—140)

The present invention relates to governors for internal combustion engines operating with injection of liquid fuel and more particularly to governors of the type in which the member that controls the injection amount, i. e., the quantity of fuel injected per injection is adjusted during normal working in dependence on the vacuum in the induction pipe of the engine.

5

The object of the invention is to provide a 10 governor of the type set forth which is adapted to check or prevent unintentional reverse running of the engine.

The pneumatic governors for controlling the 15 injection amount in internal combustion engines, whose governor chamber is connected to the air induction pipe of the engine, are dependent in their working on the direction of the current in this pipe, if the arrangement of the induction pipe producing the governing vacuum and the connection of the governor chamber to this induction pipe does not deliver the same or similar 20 pressures on a reversal of the air current as in the direction of current in the induction pipe during ordinary working. It may happen, for 25 example, in vehicle motors when on a steep ascent that the vehicle may run backwards, and the engine starts to run in the reverse direction, whereby the engine would exhaust the cylinder charge into the induction pipe and produce an 30 excess pressure in this latter. This excess pressure would be transmitted to the pneumatic governor independently of the adjustment of the throttle-valve, break the vacuum in the governing chamber and assist the returning force in 35 the governor tending to adjust the controlling member to full load. With the throttle valve closed, the excess pressure produced by the cylinder charge would be quickly transferred to the pneumatic governor, which would then adjust the 40 controlling rod to full load. The excess pressure acting on the pneumatic governor may, in this case, become so strong that it would no longer be possible for the driver, by overcoming this 45 excess pressure, to pull the governor and the controlling rod by quick action into the "stop" position. The consequence of this would be that the engine, which the driver has of course in the meantime disconnected from the driving wheels by disengaging the clutch or the gears, would 50 race uncontrolled.

In order to be able to remove this drawback, according to the invention, when an excess pressure occurs in the pipe leading from the induction pipe to the governor chamber, a branch pipe

is opened through which the excess pressure can escape.

Various forms of construction are shown by way of example in the accompanying drawings, in which—

5 Figure 1 shows an arrangement in which the connection of the branch pipe is operated by the driver

10 Figures 2 and 3 show examples of an automatically operated branch pipe.

Figure 4 is an example of another arrangement of the branch pipe.

Figure 5 shows an arrangement having the branch pipe built into the governor casing, and

15 Figure 6 a similar construction.

In the casing 1 of an injection pump of known construction the cam shaft 2 drives the pump pistons 3, which are rotatable about their axes by means of a toothed rackbar 4, and provided with an oblique edge control, and can deliver 20 according to the degree of their angular adjustment a variable amount of fuel into the cylinders of the internal combustion engine to be governed. The rackbar 4 can be adjusted by the piston 5 of a pneumatic governor 6, in the chambers 7 and 8 of which different pressure may prevail. The governor chamber 7 is connected by a pipe 9 to the induction pipe 10 of the engine, and a spring 11 in the governing chamber tends 25 to displace the piston 5 and the controlling rod 30 4 in the direction of the injection pump so as to increase the amount of fuel. The vacuum existing in the induction pipe 10 during normal running of the engine is transmitted through the pipe 9 to the governor chamber 7, and as the 35 chamber 8 is connected to the atmosphere through the opening 8a, the difference in pressure between the two chambers acting on the piston 5 can move the controlling rod 4 to the left against the action of the return spring 11 40 and cause a decrease in the amount of fuel injected into the engine.

If however, for any reason, the engine changes 45 its direction of rotation, the air current flowing to the cylinders during normal working in the direction of the arrow A changes its direction, and the cylinder contents now exhausting from the engine in the direction of the arrow B produce an excess pressure in the induction pipe and in the chamber 7 connected with the induction pipe by the pipe 9, and this pressure may be as great as, or greater than, the atmospheric pressure. The return spring 11, and the excess pressure in the governor chamber reinforcing its action, can then without hindrance move the con- 50 55

trolling rod in the direction of full load adjustment. The driver will, of course, endeavour to pull the controlling rod 4 into the "stop" position by means of a stopping lever 13 acting in known 5 manner on the piston 5 and which he can operate from the dashboard, but he will not begin to do this until he has noticed the reverse running of the engine which with the excess pressure in the governing chamber produced by the reverse 10 running of the engine, together with the pressure of the spring 11, has become very great even after a few reverse revolutions of the engine. This is explained by the circumstance that the throttle-valve 12 in the induction pipe is kept closed by 15 the driven in order entirely to cut off the feed of fuel when the vehicle begins to run in the reverse direction. The excess pressure produced in the induction pipe by the cylinder contents can therefore not escape in the direction of the induction 20 pipe, so that it acts in its full strength on the piston in the governor chamber. The driver can then no longer overcome the excess pressure on the piston 5 by the stopping lever 13, so that the engine runs uncontrolled.

25 According to the invention, a port or opening 14 leading into the open air is arranged in the pipe 9 that connects the governor chamber 7 to the induction pipe 10, and this opening is opened by a valve 15 when the engine begins to run in reverse. In the construction shown in Figure 1, the valve 15 is adjustable by hand in such a way that when the engine unintentionally begins to run in the reverse direction, the driver can by 30 operating the valve at once interrupt the connection between the pneumatic governor casing 6 and the induction pipe 10, and connect the governor chamber 7 with the atmosphere in such a way that any excess pressure that may exist in this chamber escapes into the atmosphere. A 35 suitable mode of operating the valve 15 can be obtained by its adjusting lever 16 being coupled to the stopping rod 17 by an extension 17a. This arrangement has the advantage that the valve is operated even on the stoppage of the engine during 40 ordinary running, and the port 14 opened for the quick emptying of the chamber 7. The valve 15 thus remains always ready for operation in the comparatively very rare cases of unintentional starting in the reverse direction. A clearance or lost motion is provided between the 45 stopping device 13 and the piston 5, when the latter is in the full load position, the piston and the control rod or rack bar 4 normally being held against further movement to the right by suitable stop means, not shown. This clearance or 50 lost motion is sufficiently large to enable the valve 15 in the stopping operation to cut off the pipe 9 from the induction pipe 10 and open the port 14 to atmosphere, before the stopping device 13 comes to bear on the piston 5.

55 In the construction shown in Figure 2, an automatically-acting excess pressure valve 15a is arranged in the pipe 9, through which valve excess pressure occurring in the pipe 9 and governing chamber 7 due to reversal of the engine can escape into the atmosphere, so that the driver can pull the controlling rod 4 into the "stop" position by means of the stopping device 13, the air escaping from the governor chamber through 60 the throttle opening 1a and if required also by the valve 15a.

65 In order entirely to avoid the transfer of an excess pressure to the chamber 7 of the pneumatic governor when the unintentional reverse 70 running begins, a non-return valve 18 with an

excess pressure valve 15b can be arranged in the pipe 9, as shown in Figure 3. This non-return valve 18 consists of a ball-valve, which during the ordinary running of the engine is kept open by the vacuum in the pipe 9, but which on the change 5 in the direction of flow in the reduction pipe 10 is at once closed by the excess pressure. The excess pressure valve 15b is directly combined with the non-return valve 18. It consists of a light spring-loaded ball-valve, which opens a port 14 to the 10 atmosphere as soon as the pressure in the pipe 9 closes the valve 18. The valves 15b and 18 can open the port 14 to the outside even during normal working when the piston 5 is moved into the "stop" position.

15 A throttle opening 1a leading to the atmosphere from the chamber 7 is arranged in the casting 6 of the governor, through which opening a strong vacuum in this chamber can be equalised. In such cases where, for instance in going down 20 hill, a strong vacuum is produced in the chamber 7, the valve 18 will keep this chamber closed, so that the controlling rod 4 drawn to the "stop" position against the spring 11 could even then no longer be moved when the engine is again to run 25 under full power. Even the opening of the throttle-valve 12 could change nothing in this condition because the valve 18 is held closed by the vacuum in the chamber 7. Lower vacua which cause an increase in the fuel feed could 30 then no longer act on the piston 5 if the small opening 1a were not present through which air passes from the outside into the governor chamber 7 and gradually breaks the vacuum.

35 According to a further feature of the invention, the excess pressure in the induction pipe 10 can, on the change in the direction of rotation, be transferred to the other side of the piston 5 and conveyed by means of a branch pipe 19 (Figure 4) into the chamber 8, so that it results, like the 40 vacuum does in the chamber 7, in a reduction of the fuel amount and a throttling of the engine.

45 In the construction shown in Figure 4, a branch pipe 19 from the pipe 9 is connected by a three-way cock 20 to the chamber 8 of the pneumatic 50 governor 6. By means of the cock 20 the chamber 7 can be cut off from the induction pipe, and in its place the chamber 8 connected to the induction pipe. When a change in the direction of rotation of the engine takes place the three-way 55 cock 20 can be adjusted such as by rotating it from the dashboard.

60 In the construction shown in Figure 5, the branch pipe 19a is located in the cylinder wall of the pneumatic governor 6. In this simple construction, closure valves 21 and 22 serve for controlling the pipes 9 and 19a. A ball-valve 21 is, for example so arranged in front of the opening of the pipe 9 that the ball keeps the opening open during the ordinary working condition of a 65 vacuum, but closes the opening when an excess pressure occurs. In the branch pipe 19a a ball-valve 22 acts in the opposite direction, in that the ball is raised from its seat, on which it is pressed by a spring 23, when an excess pressure 70 occurs in the pipe 9.

75 An example of construction working without a spring 23 is shown in Figure 6, in which the closure members, for instance balls 21 and 22 are provided in pipes 9a and 19a arranged in Z- 70 form. When an excess pressure occurs in the induction pipe 10, the opening of the pipe 9a closes and the ball in the branch pipe 19a opens the passage to the chamber 8, which is connected to the atmosphere by a throttle opening 8a.

We declare that what we claim is:

1. In a governor apparatus for internal combustion engines operating with injection of liquid fuel, a control member, means including a connection for connecting said control member to, and making it subject to the vacuum in, the induction pipe of the engine, said control member being adapted to control the fuel injection amount, and valve means in said connection operable to prevent an abnormal pressure from being supplied to said control member in the direction for increasing the fuel injection amount.
2. In a governor apparatus for internal combustion engines operating with injection of fuel, a chamber, a conduit leading from said chamber and connected with the induction pipe of the engine and a movable member in said chamber subject to the vacuum transmitted from the induction pipe by said conduit and adapted to govern the fuel injection amount, and valve means in said conduit operable to prevent an abnormal pressure from being transmitted by said conduit to the control member in the direction for increasing the fuel amount.
3. In a governor apparatus for internal combustion engines operating with injection of liquid fuel, a chamber, a conduit leading from said chamber and connected with the induction pipe of the engine and a movable member in said chamber subject to the vacuum transmitted from the induction pipe by said conduit and adapted to govern the fuel injection amount in dependence upon the induction pipe pressure, and means for preventing reverse running of the engine comprising a branch duct from said conduit, valve means operable to open said duct when abnormal pressure occurs in the induction pipe and means for displacing the movable member in the direction of decreasing the fuel amount, in the open position of said valve means.
4. In a governor apparatus for internal combustion engines operating with injection of liquid fuel, a chamber, a conduit leading from said chamber and connected with the induction pipe of the engine and a movable member in said chamber subject to the vacuum transmitted from the induction pipe by said conduit and adapted to govern the fuel injection amount in dependence upon the induction pipe pressure, and means for preventing reverse running of the engine comprising branch duct from said conduit, valve means operable to open said duct to atmosphere when abnormal pressure occurs in the induction pipe and means for displacing the movable member in the direction of decreasing the fuel amount, in the open position of said valve means.
5. In a governor apparatus for internal combustion engines operating with injection of liquid fuel, a chamber, a movable member in said chamber adapted to control the fuel injection amount, a conduit leading from said chamber on one side of said movable member and connected to the induction pipe of the engine, and a branch conduit from said first-mentioned conduit leading to said chamber on the other side of said movable member and valve means in said branch conduit operable to connect the chamber on said other side of the movable member to the induction pipe when abnormal pressure occurs in the induction pipe.
6. In a governor apparatus for internal combustion engines operating with injection of liquid fuel, a chamber having a restricted opening therein, a movable member in said chamber adapted to control the fuel injection amount, a

conduit leading from that side of the chamber having the restricted opening and connected to the induction pipe of the engine, and a branch conduit from said first-mentioned conduit leading to said chamber on the other side of said movable member and valve means in said branch conduit operable to connect the chamber on said other side of the movable member to the induction pipe when abnormal pressure occurs in the induction pipe.

7. In a governor apparatus for internal combustion engines operating with injection of liquid fuel, a chamber, a movable member in said chamber adapted to control the fuel injection amount, a conduit leading from said chamber on one side of said movable member and connected to the induction pipe of the engine, a branch conduit from said first-mentioned conduit leading to said chamber on the other side of said movable member and valve means in said branch conduit adapted to be automatically opened by abnormal pressure occurring in said branch conduit to connect the chamber on said other side of the movable member to the induction pipe when abnormal pressure occurs in the induction pipe.

8. In a governor apparatus for internal combustion engines operating with injection of liquid fuel, a chamber, a movable member in said chamber adapted to control the fuel injection amount, a conduit leading from said chamber on one side of said movable member to the induction pipe of the engine, a branch conduit leading from said first-mentioned conduit and connected to atmosphere and valve means at the junction of said conduits normally isolating said branch conduit from said first-mentioned conduit and dividing the first-mentioned conduit into two portions, one leading to said induction pipe and the other to said chamber, said valve means being operable to isolate said portion of the first-mentioned conduit, leading to the chamber, from the induction pipe and to connect it with said branch conduit.

9. In a governor apparatus for internal combustion engines operating with injection of liquid fuel, the combination of a chamber, a movable member in said chamber normally subject on one side to atmospheric pressure and adapted to control the fuel injection amount, a conduit leading from said chamber on the other side of said movable member and connected to the induction pipe of the engine normally to transmit a vacuum to said other side of the movable member, a branch conduit leading from said first-mentioned conduit to atmosphere, a control member at the junction of said conduits operable to isolate the vacuum side of said chamber from the induction pipe and to connect the conduit from said chamber with the branch conduit which is open to atmosphere, and a device for voluntarily displacing said movable member to its "stop" position, said control member and said device being coupled together so that on stopping, the vacuum side of said chamber is cut off from the induction pipe prior to movement of said movable member into its "stop" position.

10. In a governor apparatus for internal combustion engines operating with injection of liquid fuel, a chamber, a movable member in said chamber normally subject on one side to atmospheric pressure and adapted to control the fuel injection amount, a conduit leading from said chamber on the other side of said movable member and connected to the induction pipe normally to transmit a vacuum to said chamber, and at least one non-return valve in said conduit inter-

mediate said chamber and the induction pipe operable automatically by increase of pressure in said conduit to isolate the vacuum side of said chamber from the induction pipe when an abnormal pressure occurs in the induction pipe.

5 11. In a governor apparatus for internal combustion engines operating with injection of liquid fuel, a chamber, a movable member in said chamber dividing the chamber into two compartments and adapted to control the fuel injection amount, conduits, one leading from each compartment, connected to the induction pipe of the engine, and a non-return valve in each conduit, said valves controlling said conduits and operable by the pressures occurring therein, one of said valves closing and the other opening when superatmospheric pressure occurs in said conduits and the first valve opening and the second valve closing when subatmospheric pressure occurs in 10 said conduits to connect one or the other of said compartments with the induction pipe according to the pressure in said induction pipe.

15 12. In a governor apparatus for internal com-

bustion engines operating with injection of liquid fuel, a chamber having a conduit formed in the wall thereof and having branches leading to opposite ends of the chamber, a movable member displaceable in said chamber between the 5 points at which each branch of said conduit opens into the chamber and adapted to control the fuel injection amount, a pipe connecting said conduit with the induction pipe of the engine, and a non-return valve in each branch of said conduit, said 10 valves controlling said branch conduits and operable by the pressures occurring therein, one of said valves closing and the other opening when superatmospheric pressure occurs in said branch conduits and the first valve opening and the second valve closing when subatmospheric pressure occurs in said branch conduits to connect one or the other end of said chamber with the induction pipe according to the pressure in said induction pipe.
